UNITED STATES PATENT OFFICE.

SAMUEL D. BUTTERWORTH, OF LANSING, MICHIGAN.

LOCK

Application filed February 15, 1922. Serial No. 536,663.

To all whom it may concern:

Be it known that I, SAMUEL D. BUTTERWORTH, a citizen of the United States, residing at Lansing, in the county of Ingham and State of Michigan, have invented certain new and useful Improvements in Locks, of which the following is a specification.

This invention relates to door locks, and has for its object a door lock bolt which 10 can be dogged by setting the dog-setting devices from the face plate but which dogging devices do not become effective until the door has been closed. Hence the dog-setting devices can only be changed when the door has been opened. The door can 15 be opened without in any way disturbing them from either the outside by one who has a suitable key or from the inside by turning a suitable turn button. However, 20 the mere opening of the door does not take off the dog-setting devices.

This lock is especially designed for use in connection with a latch bolt which is retracted simply by pulling or pushing on the door. No roll-back is used with this 25 lock and no turn knobs or levers. By utilizing a dog which dogs directly on the lock bolt as distinguished from dogging the outside retractor, it is impossible to open the door with a casement knife. This 30 is possible with most night locks and it is for this reason that so many doors are provided with an additional separate dead-lock bolt.

The dogging bolt is withdrawn when one 35 opens the door either from the inside or outside but the dog-setting devices are still left in such position that the dogging bolt is automatically shot into dogging relation again when the door is closed. These 40 results make the dogging device peculiarly adapted to this type of latch which is disengaged by simply pushing or pulling on the door.

In the drawings,

Fig. 1 is an elevation of the outside of a door equipped with my lock.

Fig. 2 is an elevation of the inside of the same door.

Fig. 3 is an elevation of the lock mechanism showing the dog-setting devices "off" and the dogging bolt "off".

Fig. 4 is an elevation of the lock mechanism showing the dogging bolt "on" and the dog-setting devices "off".

Fig. 5 is a similar elevation showing the

dog-setting devices set to trip the dogging bolt which is "off".

Fig. 6 is a vertical section on the line 6—6 of Fig. 5.

Fig. 7 is a detail of the thumb turn cam.

Fig. 8 is a detail of the cylinder lock cam.

Fig. 9 is a detail of the dog-setting connecting strap.

Fig. 10 is a fragmentary view of the face plate and the dog-setting button.

Fig. 11 is a detail of the dog-setting trip.

Fig. 12 is a detail of the dogging bolt.

Fig. 13 is a detail of the dogging bolt 70 tumbler.

Fig. 14 is a vertical section through the door showing the lock casing in elevation.

Fig. 15 is a section on the line 15—15 of Fig. 3.

The lock housing is designated *a* and is secured to the face plate *b* by screws *c* screwing into the lugs *d* projecting from the back of the face plate. A sliding latch-bolt *e* has a pair of sliding rods *f* that run 80 through the guides *g*. The springs *h* tend to force the latch-bolt outward. The striker contacting surface of the bolt is a rubber roll *i*. Hence the door may be unlatched simply by pulling or pushing on 85 the handles *j* and *k* on the outside and inside of the door respectively. This form of lock is not claimed in the present application but is made the subject matter of a co-pending application Serial No. 511,761. 90

To lock this bolt so that the door cannot be opened, a dogging bolt *m* is provided, detailed in Fig. 12. This dogging bolt is always under the stress of the torsional spring *n*, tending to project it against the latch-bolt when it is released. The tumbler *o* stressed by the flat spring *p* keeps the dogging bolt withdrawn against the stress of the spring *n*, by locking behind the stationary post *q*, which is part of the lock housing 100 casting. This tumbler *o* is provided with a trip arm *r*. When the thumb turn cam *s* engages this trip arm, the tumbler is lifted up so the same is released from the post *q* and the bolt may be shot by the spring *n*. 105 This places the dogging bolt "on" but when the dogging bolt has been withdrawn to open the door it will stay withdrawn. The dogging bolt may be similarly put "on" by the cam *t* connected with the cylinder lock *u*. When the locking dog once engages the rubber roller *i* the tumbler locking lug 110

v drops in front of the stationary post q and holds the dogging-bolt so that it will be impossible to disengage the latch-bolt by means of a casement knife. In order to withdraw the dogging-bolt either the lock cam t or the thumb turn cam s has to first strike the trip end r of the tumbler and then retract the bolt by engaging the abutment x of the dogging-bolt.

10 In order to make this style of dogging-bolt effective in a latch bolt which opens simply by pushing or pulling the door, it is necessary to have dog-setting devices which can be set automatically to shoot the locking bolt "on" when the door closes although the dogging bolt has been temporarily released to permit one to push or pull the door open. These dog-setting devices comprise a two-arm trip y pivoted to the post z. A torsional spring 1 tends to keep the pin 2 in the bottom of the slot 3 in the connecting arm 4 attached to the crank 5 bent into the end of the rod 6 rotatably supported in the rib 7. On the face of the lock (Fig. 10) is a button 8 fastened to the end of the rod 6. This button may be swung through the segmental recess 9 in the face of the face plate.

When the button is in the position shown 30 in Fig. 10, the trip is set. The crank is turned to its upper position which draws the connecting arm up and sets the upper arm of the trip in the path of the cam 10 on the end of the upper bolt guide rod f. 35 Hence when the door slams shut this cam 10 carries the trip up, which acts as a bell crank lever and through its lower arm 11 engages the projection 12 on the upper side of the tumbler. This lifts the tumbler locking lug v from behind the post q and the spring n shoots the dogging-bolt in behind the latch roller or head i. Now obviously as long as the button remains in the same 40 position the trip will always be set although one enters the building from the outside and temporarily releases the dogging-bolt so that he can push or pull the door open. Nevertheless as soon as the door is again slammed shut the trip automatically comes 45 into play to shoot the dogging-bolt. The same operation occurs when one passes through the door from the inside to the outside.

On the other hand, when the trip is "off" 50 due to shifting of the dog-setting button 8 to the right in Fig. 10, one may still place the dogging-bolt against the latch head either by the thumb turn on the inside or by the cylinder lock on the outside. When 60 he releases the dogging-bolt the dogging-bolt is released for good until the trip-setting button 8 is again placed.

What I claim is:

1. In a lock, the combination of a housing, a latch-bolt slidable therein, a dogging-

member provided with a tumbler for holding it in released position or projected position where it locks the latch-bolt against retraction, means tending to project the bolt behind the latch-bolt when the dogging-member is released, dog-setting devices which can be set to be operated by the latch-bolt to release the tumbler and permit the dogging-member to shoot in behind the latch-bolt and means independent of the dog-setting devices for releasing the tumbler.

2. A lock, having in combination, a housing, a sliding latch-bolt therein, a dogging-member, means for normally tending to shoot the dogging-member behind the latch-bolt to prevent the latch-bolt from being retracted, a tumbler secured to the dogging-member for holding the same in either position of its travel, means for retracting the dogging-member, and dog-setting devices that can be set to be tripped by the latch-bolt and to trip the tumbler to permit the shooting of the dogging-member behind the latch-bolt when the door is closed.

3. A lock, having in combination, a housing, a sliding latch-bolt, a sliding dogging-member, means tending to project the dogging-member behind the latch-bolt, a tumbler for holding the dogging-member in either position of its travel, means for tripping the tumbler and retracting the dogging-member, and dog-setting devices including a trip having engagement with the tumbler and in engagement with the latch-bolt when the trip is set whereby the closing of the door serves to move the trip and disengage the tumbler permitting the dogging-member to shoot in behind the latch bolt.

4. A lock, having in combination, a housing, a sliding latch-bolt, a sliding dogging-member, means for locking the dogging-member in its retracted position, means yieldingly urging the dogging-member into its forward position to lock the latch-bolt against retraction, and dog-setting devices including a two-arm trip pivotally supported on the lock housing which may be set to bring one arm in the path of the latch-bolt and the other arm in engagement with the dogging-member holding means, whereby when the door is closed the latch-bolt operates the trip to release the dogging-member to lock the same behind the latch-bolt.

5. A lock, having in combination, a housing, a latch-bolt slidable therein, a dogging-member, a spring normally tending to project the dogging-member behind the latch-bolt to lock the latter from retraction, means for retracting the dogging-member and holding same retracted, and dog-setting devices including a trip which can be set into the path of the latch-bolt and which engages with the dogging-member holding means

- whereby closing of the door operates the trip to release the dogging-member so it may be shot behind the latch-bolt to hold the latter from retraction, said dog-setting devices including also a crank arm having a connection with said trip member and a crank-actuating member exposed on the face plate of the lock. 40
- 5 6. A lock having in combination, a housing, a latchbolt slidable therein, a dogging-member, a spring normally tending to project the dogging-member behind the latch-bolt to lock the latter from retraction, means for retracting the dogging-member and holding same retracted, means for releasing the dogging member from the retracted position, and dog-setting devices including a trip which can be set into the path of the latch-bolt and which engages with the dogging-member holding means whereby closing 45
- 10 of the door operates the trip to release the dogging-member so it may be shot behind the latch-bolt to hold the latter from retraction. 50
- 15 7. A lock, having in combination, a housing, a latch-bolt slidable therein, a dogging member provided with a control member for holding the dogging member in an interfering position and in a non-interfering 55
- 20 position, means for actuating said control member to release the dogging member from a non-interfering position to an interfering 60
- 25 position, and dog-setting devices which actuate the control member upon the closing 65
- 30 of the door for releasing the dogging member from the non-interfering position so it may be shot into the interfering position to hold the latch-bolt from retraction. 35
- 35 8. A lock, having in combination, a housing, a latch-bolt slidable therein, a dogging-member provided with a control member adapted to hold the dogging-member behind the latch bolt to lock the latter from retraction, and to hold said dogging member in retracted position, means for actuating said control member and a trip actuated by the closing of the door which engages said control member for releasing the dogging member so it may be shot behind the latch bolt to hold the latter from retraction. 55
- 40 9. A lock, having in combination, a housing, a latch-bolt slidable therein, a dogging-member provided with a control member adapted to hold the dogging-member behind the latch-bolt to lock the latter from retraction, and to hold said dogging member in retracted position, means for actuating said control member to release said dogging member and dog-setting devices including a trip which can be set into the path of the latch-bolt and which engages with the control member whereby closing of the door operates the trip to release the dogging-member so it may be shot behind the latch-bolt to hold the latter from retraction. 60
- 45 35
